UNITED STATES PATENT OFFICE.

THOMAS JOSEPH STURTEVANT, OF WELLESLEY, MASSACHUSETTS, ASSIGNOR TO
STURTEVANT MILL COMPANY, A CORPORATION OF MAINE.

BEARING FOR ROLLS OF CRUSHING-MILLS.

1,164,672.

Specification of Letters Patent. Patented Dec. 21, 1915.

Application filed October 9, 1912. Serial No. 724,887.

To all whom it may concern:

Be it known that I, THOMAS J. STURTEVANT, a citizen of the United States, residing at Wellesley, in the county of Norfolk and State of Massachusetts, have invented or discovered certain new and useful Improvements in Bearings for Rolls of Crushing-Mills, of which the following is a specification, reference being had therein 5 to the accompanying drawings.

This invention relates to ring roll crushing mills of that class shown by U. S. Patents No. 906,829, dated December 15, 1908, and No. 995,580, dated June 20, 1911. A 10 mill of the class referred to comprises an anvil ring rotating on a fixed axis and one or more crushing or hammer rolls co-operating therewith and forced outward toward the anvil ring by spring pressure against 15 the material which is subjected to the crushing or pulverizing action between the hammer roll or rolls and the anvil ring. Owing to the very heavy duty which is placed on these crushing rolls, which operate, in the 20 larger sizes of mills, under a pressure of several tons, it is necessary that the bearings should be of such a character as to 25 reduce the resulting friction to a minimum, and it is also necessary that these bearings 30 should be thoroughly lubricated. These rolls operate in a chamber which is filled with gritty dust, resulting from the pulverization of hard material, and it has heretofore been found practically impossible 35 to exclude this gritty dust from the bearings of the rolls, so that undue wear of the roll bearings has resulted, requiring frequent renewal of parts.

The present invention has for its object 40 to obviate this difficulty by providing an anti-friction roller bearing device for the crushing rolls, as also by providing means whereby said anti-friction roller bearing may be thoroughly lubricated and gritty 45 dust be excluded therefrom, as will herein-after more fully appear.

In the accompanying drawings Figure 1 50 is a longitudinal sectional view, partly broken away, illustrating the present invention. Fig. 2 is a partial end view looking from the left of Fig. 1. Fig. 3 is a cross section of the roll and roller bearing on line 3-3, Fig. 1. Fig. 4 is an elevation, partly in vertical section, of a crushing mill embodying the present invention.

Referring to the drawings, 12 is a roll-supporting shaft which, when in place in the crushing mill, is hung on a pivoted carrier mounted on the end head of the frame or casing of the mill, and which pivoted carrier is acted on by spring pressure which is transmitted to the crushing roll, as fully shown and described in the patents above referred to. Mounted on the shaft 12 is an anvil or crushing roll 13 which, in practice, 60 has a chill-hardened outer surface so as to be able to withstand the wear; the said roll having an interior bore or chamber of such a size as to receive a series of anti-friction rollers 14 interposed between the 65 said shaft 12 and the said roll 13. The anti-friction rollers 14 are mounted in a cage comprising end heads or rings 15 secured together by shouldered spacing bolts 16, riveted at their ends, the said anti-friction rollers working between buttons or 70 plugs 17 mounted in the said end impinging against the ends of the rollers 14, these buttons or plugs heads or rings and serving to limit endwise movements of said 75 rollers.

Attached to the inner face of the crushing roll 13, by screws or bolts 18, is a ring 19 overlapping one end of the bearing roller cage, to retain the latter within said roll, 80 and having an interior annular flange 20 to which are attached two brass thrust rings 21, one located on each side of said flange, these thrust rings being opposite to or overlapping the end of the shaft 12. The shaft 90 12 is formed hollow for the purpose of admitting lubricating oil to the bearings of the roll 13 from an oil cup 22 which is secured to said shaft by a hollow screw plug 23. The said oil cup is high enough so that 95 oil will flow by gravity to the roller bearings.

Screwed into the inner end of the hollow bearing shaft 12 is a hollow plug 24 having a body portion 25 provided with openings 100 for the escape of oil and having a head portion 26 between which and the end of the shaft 12 the thrust rings 21 are located. The said plug 24, when screwed into the said shaft 12, is locked in place and prevented from turning by a key 27 entering the end of the said shaft 12 and engaging said plug, said key being in turn held in place by a cotter pin 28 passing through the exposed end of the said key and a pro- 105 110

jection 29 on the end of said plug. Attached to the ring 19, by screws or bolts 30, is a cap 31 which, with the ring 19, forms a tight closure for the inner end of the bearing chamber, to prevent the escape of oil, the said cap 31 being removable to afford access to the plug 24 which serves to hold the crushing roll and its bearings on the shaft 12. When the said plug is unscrewed and removed from the shaft 12 the roll 13 and its bearing, completely assembled, may be slipped off the end of the shaft.

Secured to the outer face of the roll 13, by bolts 32, is a cylindrical box 33 through which the shaft 12 passes. The lower part of the chamber of said box, between the inner inwardly projecting wall or flange 34 and the outer inwardly projecting wall or flange 35, serves as a dust and oil catching trap to receive waste oil escaping from the bearing of the roll 13. The said box 33 extends outward through an opening in the end wall 44 of the casing forming the chamber of the mill; and as the inner flange 34 is somewhat deeper or higher at its lower part than the outer flange 35 the surplus oil, when the trap in the bottom of the said box is filled, will flow over the upper edge 30 of the last-named flange, and thus be discharged or permitted to escape outside of the chamber of the mill. In crushing some kinds of material it is very objectionable to have any oil get into the pulverized product, 35 but by virtue of the construction hereinbefore described, and which affords an oil tight chamber in which the bearings of the roller 13 are inclosed, oil will be prevented from entering the chamber of the mill, and 40 any surplus oil coming from the said bearings will be discharged outside of the mill casing, and outside of the pulverizing chamber. Surplus oil may be prevented from creeping out on the shaft 12 by means of a 45 check ring 37, of felt or other suitable material, surrounding the said shaft and retained in place by a holder 38.

From the foregoing it will be understood that the crushing roll 13 is mounted on anti-friction rollers 14 running between what may be termed an outer race afforded by the inner surface of the said crushing roll and an inner race afforded by the outer surface of the shaft 12, and that while lubricating oil may be freely fed to the roller bearings for the said crushing roll, the chamber in which said bearings are inclosed is oil tight with reference to the mill chamber, so that no oil can escape from said bearing chamber into the chamber of the mill, while surplus or waste oil will be conveyed outward and discharged outside the mill casing. It will also be understood that when it is desired to replace crushing rolls which

may have become worn in use, this can 65 readily be done by removing the cap 31 and the holding plug 24, after which the assembled roller bearings and crushing roll may be readily slipped off from the shaft 12; while when the crushing roll is performing its duty it will run with comparative ease and little friction owing to the fact that it is mounted on roller bearings which may be kept thoroughly lubricated at all times. 75

By reference to U. S. Patents Nos. 606,829 and 995,480, hereinbefore referred to, it will be understood that the shaft 12, carrying the crusher or hammer roll 13, will, in practice, be acted on by a spring or springs 80 which will serve to press the hammer roll yieldingly toward the crushing face of the anvil ring, thereby cushioning the action of the hammer roll and affording a certain elasticity to its supporting shaft or holder 85 12. Owing to the fact that the hammer roll 13 will thus be yieldingly mounted, the anti-friction rollers on which the said hammer roll runs are much less liable to become broken or injured in the operation of the 90 hammer roll than would be the case if the said roll were not thus yieldingly or elastically supported. Owing also to the fact, as shown by the patents above referred to, that the tension of the spring or springs, 95 acting on the hammer rolls of the machines of the class to which the present invention relates, may be adjusted or varied, it will be understood that the hammer roll 13 will be adjustably held to its work by a predetermined pressure, and which pressure may be increased or diminished, as may be found best. This will be clearly understood by reference to Fig. 4 of the drawings in which 39 denotes the rotating mill shaft on which 100 is fixedly mounted a spider or head 40. The anvil ring 41, with which the crushing rolls 105 13 coöperate, is secured to said head 40 to rotate therewith. The roll-supporting and non-rotating shafts or bearing pins 12 are 110 mounted in carriers 42 which are pivoted, as at 43, to the removable end casing part or head 44 of the mill casing 45, these casing parts 44 and 45 forming the chamber of the mill. The carriers 42 are acted on by springs 115 46 acting through a three-armed spider 47, a pressure regulating screw 48, a disk 49 and ball-bearing parts 50, all as fully set forth in the patents hereinbefore referred to and also U. S. Patent No. 1,000,457, dated 120 Aug. 15, 1911.

Having thus described my invention I claim and desire to secure by Letters Patent:

1. The combination with a rotating member and a non-rotating shaft on which the 125 same is mounted, of anti-friction bearing rollers interposed between the said member and shaft, a cage in which the said anti-fric-

tion rollers are mounted, a ring directly attached to one end of said rotating member and overlapping one end of said cage, said ring serving to retain the said cage within 5 said rotating member so that said rotatable member and its assembled roller bearing may be handled as a unit in being placed on or removed from said shaft, said ring having an inwardly extending flange, a plug attached to said shaft and having a head overlapping said flange, and a removable cap attached to said ring.

2. The combination with a rotating member and a non-rotating shaft on which the 15 same is mounted, of anti-friction bearing rollers interposed between said member and shaft, a cage for holding said rollers, a ring directly attached to one end of said rotating member to form an assembled connection 20 between the latter and said cage and rollers, so that these assembled parts may be handled as a unit, a plug screwed into said shaft and coöperating with said ring to secure the rotating member and shaft together, a removable key for locking said plug to prevent the same from turning, means for holding 25 said key in place, and a removable cap attached to said ring and which cap may be taken off when access to said key and screw- 30 plug is necessary.

3. The combination with a rotating member and a non-rotating hollow shaft on which the same is mounted, anti-friction bearing rollers interposed between said member and 35 shaft, a cage for holding said rollers, a ring attached to one end of said rotating member to form an assembled connection between the latter and said cage and rollers, a plug screwed into said shaft and coöperating 40 with said ring to secure the roll and shaft together, a removable key for locking said plug to prevent the same from turning, means for holding said key in place, and a removable cap which may be taken off when 45 access to said key and screw plug is necessary, said plug having a duct or conduit for

the passage of oil from said hollow shaft to the chamber containing said bearing rollers.

4. The combination with a rotatable member and a non-rotating shaft on which the 50 same is mounted, of anti-friction bearing rollers interposed between said member and shaft, means for feeding oil to said bearing rollers, walls forming a chamber for said bearing rolls, means for tightly closing the 55 inner end of the said chamber, a box attached to the outer face of the said rotatable member and into which said chamber opens so that said box will serve as a trap to receive and discharge the surplus oil from said 60 chamber.

5. The combination with a rotatable member and a non-rotating shaft on which the same is mounted, of anti-friction bearing rollers interposed between said member and 65 shaft, means for supplying a lubricant to said bearing rollers, walls forming a chamber in which said bearing rollers are inclosed, said chamber being oil-tight at its inner part but having an oil-escape opening 70 at its outer part, and a trap to receive and discharge waste oil from said chamber.

6. The combination with a rotatable member, and a non-rotating shaft on which the same is mounted, of anti-friction bearing 75 rollers interposed between said member and shaft, means for supplying a lubricant to said bearing rollers, walls forming a chamber in which said bearing rollers are inclosed, said chamber being oil-tight at its 80 inner part but having an oil-escape opening at its outer part, and a trap secured to and thus rotating with said rotating member, said trap serving to receive and discharge waste oil from said chamber. 85

In testimony whereof I affix my signature, in presence of two witnesses.

THOMAS JOSEPH STURTEVANT.
